(57) **CLAIM**

The ornamental design for a flatware handle, as shown and described.

DESCRIPTION

FIG. 1 is a top plan view of a flatware handle showing my new design;

FIG. 2 is a side view thereof; the opposite side view being a mirror image thereof; and,

FIG. 3 is a bottom plan view thereof.

The spoon shell is shown in broken lines for illustrative purposes only, and forms no part of the claimed design.
